AUTOMATIC GENERATOR REGULATOR

Alvin Colanduoni, Somerville, N. J.

Application September 22, 1933, Serial No. 690,616

1 Claim. (Cl. 171—313)

The object of the invention is to provide a device to be used as a part of an automobile equipment to function in conjunction with the charging generator, so that the latter may be set at a maximum charging rate for the combined load of the lights and battery and the output automatically regulated, so that it is cut down in proportion as the light load, or the load of any other appliance comprised in the equipment, is cut out of circuit; and to provide a device of the kind indicated which is of simple form, susceptible of cheap manufacture, and of a character that will permit it being installed in any motor vehicle without modification of any of the equipment thereof.

With this object in view, the invention consists in a construction and combination of parts of which a preferred embodiment is illustrated in the accompanying drawing but to which embodiment the invention is not to be restricted. Continued use in practice may dictate certain changes or alterations and the right is claimed to make any which fall within the scope of the annexed claim.

In the drawing:

Figure 1 is an elevational view of the invention with the case cover in open position.

Figure 2 is a sectional view on the plane indicated by the line 2—2 of Figure 1.

Figure 3 is a diagrammatic view showing the method of connecting the invention in circuit with the electrical equipment of a vehicle, such as a bus.

In the use of the invention, the third brush 10 of the generator 11 is set to provide the maximum output for charging the battery and carrying the additional load of the lights or other appliances which may form a part of the electrical equipment of the vehicle. But in series with the third brush 10, so as to be included in the field circuit of the generator, is a resistance 12 which is tapped at intermediate points in its length. Preferably the resistance consists of a series of resistance elements 14 wound on suitable heat insulating cores and serially connected together at their binding posts 15, the whole series of resistances being secured by said binding posts, on a base 16 of insulating material which is secured by means of fasteners 17 on bosses 18 formed on the back wall of a case 19 in which the resistance and its component parts are mounted.

Each resistance element is shunted with a circuit closer of which each comprises a fixed contact 20 and a movable contact 21, the latter being an armature of an electromagnet 22. One terminal

of each electromagnet is grounded as indicated at 23 and this connection may be effected in each instance by connecting the terminal with the metal of the case 19. The other terminal of each magnet is carried to a binding post 24 which is preferably mounted in one side wall of the case 19 from which it is insulated.

The extremities of the resistance 12 which consists of the several resistance elements are connected to the binding posts 25 and 26 mounted in the opposite side wall of the casing 19 from the binding posts 24, these two binding posts being similarly insulated from the case.

In connecting the invention in circuit, the connection between the third brush 10 and the field 15 of the generator 11 is split and the two leads thus provided are connected to the binding posts 25 and 26, while the binding posts 24 are connected one each to each of the switches 27 which, in the illustrated embodiment, control respectively the inside lights, the heater, the sign and the head and tail-lights, it being assumed that the invention in this instance is being used on a bus. But the binding posts 24 are connected to that side of each of the switches 27 to which the controlled devices are connected, or in other words, to those poles of the switches complementary to the poles to which the generator is connected, so that when any one of the switches 27 is closed, its attendant magnet 22 will be simultaneously thrown in circuit, so as to attract its armature 21 and thus effect the closing operation of the circuit closer shunting that particular increment 14 of the resistance 12.

When all of the switches 27 are open, the full resistance 12 is effective in the field circuit of the generator, so that its output is reduced to that necessary only to effect the charging of the battery 28. When any or all of the switches 27 are closed, either all of the resistance 12 is cut out of circuit, or such increments as are associated with the particular switch 27 which is shifted to closed position. Thus if the switch 27 controlling the sign be the only one closed, one resistance element 14 is cut out of circuit and the resistance in the field circuit is reduced to just the amount which is sufficient to raise the output of the generator to take care of the increased current necessary to place the sign lights in circuit. And so it is with any of the other appliances or lights controlled by the different switches 27.

In order to provide for fine adjustments in initial installation, each binding post 15 carries a metallic strip in the form of a finger 29 bearing upon the surface of the wire constituting the resistance of each resistance element 14. The arm

29 is frictionally supported on the binding post and may be swung to bridge two or more of the convolutions of resistance wire, so as to short-circuit the same. By this means convolutions of 5 resistance may be cut into or out of circuit, so that each increment of resistance may be adjusted to a nicety to function to effect the generator field circuit in such a way that the output of the generator will be changed to satisfy the current demand for the particular appliance associated with 10 that increment of resistance.

The invention having been described, what is claimed as new and useful is:

15 In combination with a charging generator of a motor vehicle and the light circuit thereof consisting of a plurality of switch controlled circuits in multiple, a metallic case mounted in the vehicle, a resistance mounted in said case and comprising

a plurality of serially connected resistance elements in series with the field circuit of the generator, a circuit closer shunting each resistance element and comprising fixed and movable contacts, and magnets for which the movable contacts act as armatures and connected one across each of said multiple circuits, the circuit closers being normally on open circuit and moved to closed circuit only on energization of the magnets, each resistance element being provided with a pivotally mounted finger electrically connected with one terminal, the free extremity of the finger being in superficial contact with the resistance element between the terminals thereof to progressively short-circuit increments of resistance to 15 effect nicety of adjustment.

ALVIN COLANDUONI.
